UNITED STATES PATENT OFFICE.

PLUS RAND LEVI, OF CHARLESTON, WEST VIRGINIA.

DISPENSING ATTACHMENT FOR CANS.

1,380,662.

Specification of Letters Patent.

Patented June 7, 1921.

Application filed February 18, 1920. Serial No. 359,530.

To all whom it may concern:

Be it known that I, PLUS RAND LEVI, citizen of the United States, residing at Charleston, in the county of Kanawha, and State of 5 West Virginia, have invented certain new and useful Improvements in Dispensing Attachments for Cans, of which the following is a specification.

This invention relates to dispensing appliances for cans.

For the purpose of dispensing the contents of cans which contain condensed milk, evaporated milk, or cream, syrup or other products of a liquid nature, it is customary 15 to punch two holes in the top of the can at diametrically opposite points through one of which openings the contents may flow when the can is tilted and through the other of which openings air may enter to replace 20 the discharged liquid. This method, however, is generally unsatisfactory for one does not always have at hand an implement suitable for use in punching the holes in the can top and not all implements which are sometimes used for this purpose can be employed 25 without liability of injuring one's hands. Furthermore if the contents are discharged slowly through an opening punched directly in the top of such a can, it is likely that the 30 contents will run down the side of the can and be spilled, and at the same time insanitary conditions are created as the liquid is liable to coagulate or harden about the opening in the can and accumulate dust and dirt 35 which will contaminate other portions of the contents subsequently poured from the can. Also the opening which is to serve the purpose of a vent is liable to become clogged or, if it remains open, dirt is liable to enter the 40 can through this opening. It is therefore one of the primary objects of the present invention to provide a dispensing appliance which may be applied to the top of any ordinary can in which liquid food products are 45 placed upon the market and which, at the time of its application will be caused to pierce discharge and vent openings in the can top at the proper points of location and in a manner to best provide for the dispensing 50 of the contents of the can and without any likelihood of injury to one's hands in adapting the appliance to the can.

Another object of the invention is to pro-

vide an appliance for the purpose above described which will embody a spout the lower 55 end portion of which constitutes means for piercing the can top to provide the discharge opening and which opening is occupied by the said spout, the upper end portion of the spout being so formed as to best adapt it for 60 the discharge of the contents of the can without likelihood of spilling or wasting any portion of the contents and creating insanitary conditions in the vicinity of the discharge opening in the can top.

A further object of the invention is to so construct the appliance that it may be adapted to cans of various diameters and will be securely held to the can after application, without the necessity of resorting to 70 any mechanical adjustments of parts.

A further object of the invention is to so construct the appliance that it will constitute a convenient means for handling the can both in carrying the can from place to 75 place and in pouring the contents from the can.

In the accompanying drawings:

Figure 1 is a perspective view of the device embodying the present invention applied to a can;

Fig. 2 is a view partly in side elevation and partly in section illustrating the device applied and the can tilted to pouring position;

Fig. 3 is a perspective view of the device removed from the can.

The device embodying the present invention, except for the pouring spout thereof, is preferably formed from a single integral 90 strip of resilient metal and comprises a top member which is indicated in general by the numeral 1 and which at its forward end is formed with a gripping jaw 2 which depends therefrom substantially at right angles 95 and which is preferably transversely curved as indicated by the numeral 3 to conform generally to the cylindrical contour of a can body of the ordinary size. This jaw 2 has its lower end portion deflected in an outward direction as indicated by the numeral 4 so that this end of the jaw may readily ride over the upper edge of one side of the can in fitting the appliance to the can. At its opposite end, the top or body member is 100 curved downwardly as indicated by the nu-

meral 5 to provide a hand grip or handle 6, and the strip from which the device is formed is bent as at 7 at the lower end of the handle 6 to provide an upwardly extending clamping jaw 8 which, as in the case of the jaw 2, is also curved transversely to fit the side of the can. As stated the strip from which the device is formed is of resilient metal and normally the jaws 2 and 8 will be sprung slightly inwardly toward each other and the distance between the opposing faces of the jaws will be somewhat less than the diameter of the smallest size of can in connection with which the appliance 15 is designed to be used. However, due to the resiliency of the device it will be evident that the same may be applied to cans of greater diameter as the jaws 2 and 8 may be relatively sprung apart without, however, distorting the top or body member of 20 the appliance. It will also be evident that the bend 7 which connects the handle 6 and jaw 8 is a rounded bend and that the outer surface thereof provides a rounded face located opposite the deflected lower end portion 25 of the jaw 2 so that the jaw 8 may likewise readily ride over the upper edge of a can to which the appliance is to be fitted. It will also be apparent that the jaws 2 and 30 8 will grip the diametrically opposite sides of the body of the can, which is indicated in the drawings by the reference letter C, frictionally with a sufficient degree of firmness to insure of the appliance being securely held upon the can after its application there to and yet to permit of its removal when required. The can top is indicated by the reference character C' and ordinarily the 35 top will be provided with a flange C² circumscribing the upper end of the wall of the can body. The upper end of the jaw 8 is not secured to the top or body portion 1 of the appliance but is always disconnected therefrom and may terminate slightly short 40 of the said top or body portion and, when the device has been applied to the can, may be brought into engagement with the lower edge of the flange C² in the manner shown in Fig. 2 of the drawings so as to positively 45 lock the appliance in place. This locking engagement between the parts is, however, not essential but the fact will be appreciated that the appliance is so constructed that advantage may be taken of the presence of the 50 flange C² for the purpose of additionally providing against displacement of the appliance, where the can to which the appliance is fitted is provided with such a flange. 55

To provide for dispensing of the contents 60 of the can, the appliance embodies a discharge or pouring spout which is indicated in general by the reference numeral 9 and this spout comprises a tubular body which is fitted and secured through the portion 1 65 of the appliance adjacent the juncture of

this portion with the upper end of the jaw 2, the spout projecting both above and below the plane of the said portion 1. Thus its portion which projects above the plane of the portion 1 and which is indicated by the 70 numeral 10, constitutes its discharge end and may be cut at an angle to best provide for the discharge of liquid therethrough. At its lower end the spout 9 is formed with diametrically oppositely located sharp edged 75 prongs 11 which project downwardly and which are designed to pierce the top C' of the can when the appliance is fitted to the can and forced downwardly thereon and thus forms in the said top an opening 80 through which the lower portion of the spout 9 projects in the manner clearly shown in Fig. 2 of the drawings and which opening is occupied by this spout so long as the appliance is in place upon the can. It will be 85 understood, of course, that if desired any small stopper or the like may be employed in connection with the spout 9 to close the same when the can is not in actual use and thus prevent the entrance of dust or dirt 90 through the spout.

In order to form a vent opening in the top of the can, the portion 1 may be formed with meeting incisions and the material between these incisions may be struck down to 95 provide a piercing prong 12 for the purpose stated. This prong is located between the upper end of the jaw 8 and the spout 9 and is, of course, designed to pierce the top of the can at a point diametrically opposite the 100 point at which the spout is forced through the can top.

Having thus described the invention, what is claimed as new is:

1. A device of the class described comprising a resilient strip-like body to extend across the top of a can, one end portion of the body being extended downwardly for engagement against one side of the body of the can, the other end portion of the body 110 being extended downwardly and inwardly to provide a handle portion, and beyond the handle portion being bent to extend upwardly to provide a gripping jaw portion to engage the opposite side of the can, a spout 115 extending through the body near the first mentioned end portion thereof and above and below the said body and provided with a piercing lower end, and a piercing element 120 formed up from the body near the said handle.

2. A device of the class described comprising a resilient strip-like body to extend across the top of a can, one end portion of the body being extended downwardly for engagement against one side of the body of the can, the other end portion of the body being extended downwardly and inwardly to provide a handle portion, and beyond the handle portion being bent to extend up- 130

wardly to provide a gripping jaw portion to engage the opposite side of the can, a spout extending through the body near the first mentioned end portion thereof and 5 above and below the said body and provided with a piercing lower end, and a piercing element formed up from the body near the

said handle, the first mentioned end portion of the body and the portion beyond the handle being transversely curved to conform to 10 the curvature of the can body.

In testimony whereof I affix my signature.

PLUS RAND LEVI.
